(57) **CLAIM**

The ornamental design for a orthotic with triangular heel design, as shown and described.

DESCRIPTION

FIG. 1 is a top plan view of an orthotic with triangular heel design showing our new design;

FIG. 2 is a bottom plan view thereof;

FIG. 3 is a side elevation view thereof with the orthotic upside down;

FIG. 4 is a side elevation view thereof with the orthotic right side up;

FIG. 5 is a front elevation view thereof;

FIG. 6 is a rear elevation view thereof; and,

FIG. 7 is a bottom perspective view thereof.

Each figure is a view of one orthotic for one shoe. The orthotic to be placed in the opposite shoe would be a mirror image of the view shown.
